COLOSTOMY DEVICE

Robert B. Deahl, Goshen, Ind.

Application May 27, 1949, Serial No. 95,827

6 Claims. (Cl. 128—283)

1

This invention relates to improvements in colostomy devices, and particularly to a device of this character usable by a person who has undergone a colostomy operation, in connection with the performance of a colonic irrigation.

Persons who have undergone colostomy operations usually require colonic irrigations at regular intervals. Such irrigations are rather difficult for the patient to perform by the means presently available. Thus irrigation discharge incident to peristalsis commonly results in splattering of the discharge material which creates a disagreeable condition. For this reason some physicians recommend that an individual assume a seated position in a bathtub during the irrigating operation. Some devices to avoid such a condition have been developed, but all have had some disadvantage which has made use thereof difficult, or has failed in some respect to satisfy all requirements for a practical and satisfactory device.

The primary object of this invention is to provide a device which is easy to apply and to use, which is effective for its intended purpose and overcomes the difficulties aforementioned, which fits naturally to the body, and which is easy to clean.

A further object is to provide a colostomy device which enables a person to perform a colonic irrigation while seated in a comfortable position with the hands free.

A further object is to provide a colostomy device which may be worn during colonic irrigation, which controls and guides the discharge from the irrigation while the patient is in a comfortably seated position, which can be flushed and at least partially cleaned while it is being worn, and which facilitates manipulation of a catheter therethrough and is readily sealed upon removal of the catheter from the catheter receiving opening.

Other objects will be apparent from the following specification.

In the drawing:

Fig. 1 is a view of the device in front elevation.

Fig. 2 is a vertical transverse sectional view of the device taken on line 2—2 of Fig. 1 and illustrating a slightly modified embodiment thereof.

Fig. 3 is a transverse horizontal sectional view taken on line 3—3 of Fig. 2.

Referring to the drawing which illustrates the preferred embodiment of the invention, the numeral 10 designates a backing plate or member which is preferably formed of rubberized fabric and is characterized by an enlarged central por-

2

tion of substantially circular outline, from which project two end portions 12 of elongated character. The backing plate is elongated and may be shaped substantially as illustrated in Fig. 1, wherein the terminal or arm portions 12 are of slightly greater width than the neck portions 14 which connect said arm portions to the generally circular central portion. The backing plate may be formed of hard rubber, sheet metal, rigid fiberboard, or any other material found suitable, and preferably a material which is strong, easy to clean, and resistant to water. A pad 16 is secured to the central enlarged portion 10 of the plate. The pad 16 may be formed of any material found suitable, and in the preferred form constitutes a disk of soft rubber of substantially the same size as the central portion 10 of the backing plate. Alternatively, the pad may be formed from sponge rubber, or may be a cushion constituting a flexible envelope and a filler. In each instance, however, it is preferred that the pad shall be waterproof so that it may be cleaned easily. The pad may be secured to one surface of the plate 10 by any suitable means. Thus where soft rubber or sponge rubber is used, the same may be cemented to the surface of the plate 10.

At the surface of the plate 10 opposite that to which the pad 16 is secured, is secured a second elongated panel or strap 18 as shown in Fig. 1. The panel 18 may be stitched, stapled, cemented or otherwise secured to the plate 10, and its longitudinal center line preferably substantially coincides with the longitudinal center line of the backing member 10—14. The ends of the panel 18 preferably terminate in hooks or loops 20 spaced from the outer ends of the portions 12 of the backing plate and adjacent to the restricted portions 14. Alternatively, a pair of straps or brackets 19, as best illustrated in Fig. 3, may be cemented, stitched or otherwise secured to plate 10 in spaced relation, as at the reduced portions 14 of the backing plate, which straps or brackets are provided with loop portions 20'. An eye member 22, which may be of substantially D-shape or semi-circular construction as illustrated, has a straight run or portion 24 thereof pivotally received within the hook or loop 20 or 20' as the case may be, to be retained thereby and to be free to swing about its run 24 as an axis. The eyes 22 are adapted to cooperate with and be engaged by the hooks 26 forming parts of buckles or fixtures 28 which are anchored upon the opposite ends of a belt 30. The belt is adapted to pass around the waist of the user and to be quickly and easily connected with the colostomy device.

3

by engagement of the hooks 26 with the eyes 22 upon the device, as will be apparent. Observe in this connection that the laterally projecting arm portions 12 of the backing plate bear against the buckles or fittings 28 and protect the user against the discomfort of contact of such buckles with the skin. In other words, the backing plate has a large flat smooth surface area which is engageable with the body and prevents the application of a concentrated pressure at any point of the body except through the pad, and also tends to prevent the possibility that the skin of the user will be pinched during the application and wearing of the device.

A hollow elongated member 32 is secured to and carried by the backing members 10 and 18 substantially centrally of said backing members. The member 32 is preferably formed from rubber or other flexible waterproof material and, in the preferred form, is made from molded rubber. The transverse cross-sectional shape of the member 32 is preferably substantially oval, as illustrated in Fig. 3, for the major portion of its length to provide a substantially flat rear wall portion 34 and front wall portion 36. The rear wall 34 is secured to the plate 18 in face engagement therewith, as by means of a cement or other agent for bonding the container to the plate, although any other means found suitable may be employed to secure the member 32 to the plate 18 in the Fig. 1 embodiment. In the embodiment illustrated in Figs. 2 and 3 the rear wall 34 is cemented, bonded or otherwise secured to the backing plate 10 between the brackets 19. It will be observed in both the Fig. 1 and the Fig. 2 embodiments that the points of anchorage of the wall 34 of the member 32 to its support are located at the upper end of the member 32 so that the member 32 depends from the plate 10—14. The upper end of the member 32 is closed by a top wall 38' preferably integrally formed with the member 32 as by molding of said member. Also in the preferred form, the lower portion of the member 32 is of restricted size at 38 and has an opening 40 at its lower end through which the contents of the member 32 may be discharged by gravity, the member 32 thus resembling the shape of an inverted bottle. The restriction of the size of the member 32 at its lower end is preferred but not essential and, where used, serves to facilitate the suspension of the member 32 between the legs of the user.

Inasmuch as the member 32 is preferably formed of molded rubber or other flexible material having a tendency to collapse unless supported, it is desirable to provide some means therein to shape the device and prevent collapse or flattening thereof. Such means can be provided as best illustrated in Figs. 2 and 3 and may constitute a sheet of metal or other rigid material 42 bent into C-shape and fitting within the upper portion of the member 32, as best shown in Fig. 2. This C-shaped metal member may be cemented or otherwise suitably secured to the walls of said member, and especially where formed of metal will be provided with a coating of protective material (not shown) such as a layer of rubber. Such a rubber layer is used to prevent the possibility of corrosion or rusting of the metal and also to facilitate the cleaning of the interior of the device.

A fitting 44, preferably in the nature of a nipple, is mounted in the top of the member 32, and, as shown, the top 38' is provided with a central

4

aperture. Spaced flanges 46 upon the inner end of the nipple provide a circumferential groove within which the portion of the top 38' surrounding the nipple receiving hole in the top 38' fits snugly. A suitable bonding agent or cement may be employed to hold the nipple in its proper position. The nipple projects upwardly above the member 32 and is adapted for detachable connection of a rubber or other flexible and extensible tube therewith, such as the tube 48 illustrated in dotted lines in Fig. 1.

An opening 50 is formed in the device and extends through the backing plate 10, the pad 16, and the wall 34 of the member 32. It will also be understood that in the event the member 42 is of continuous oval construction rather than C-shape construction as illustrated in Fig. 3, the opening 50 will likewise extend therethrough if said member 42 is positioned at the level shown in Fig. 2. Thus it will be seen that when the device is applied to the body of the user, the opening 50 will register with the colostomy tube in the body and will place the interior of the member 32 in communication with that colostomy tube. The opening 50 will preferably be of a size sufficiently large to contact the body space outwardly from the colostomy tube.

An opening 52 is formed in the front wall 36 of the member 32 preferably in substantial alignment with the opening 50 and is of substantially the same size as the opening 50. As here illustrated, the opening 52 also is formed in the member 42. A closure plug 54 is adapted to fit in and seal the opening 52, as best illustrated in Figs. 1 and 2. This plug is preferably formed of rubber or other suitable flexible or yielding material and may have a small circumferential bead or lip 56 formed at its inner end and an enlarged flange 58 formed at its outer end so that the plug will hold itself in place in the opening 52, being positioned by the seating of its central portion between the bead 56 and the flange 58 within the opening 52. A lug 60 may project from the plug, as at its center, and be apertured to receive a swivel link 62 to which is secured one end of a flexible cord, chain or cable 64. The opposite end of the member 64 will preferably be secured to a ring 66 encircling the nipple 42 and rotatable thereon, said ring as here illustrated preferably being provided with a protecting eye 68 to which the member 64 may be anchored.

In the use of the device, assuming that a strap or belt of proper length to fit the girth of the user is provided, the device may be applied by engaging the hooks 26 with the eyes 22. The pad 16 will be in contact with the body and will cushion the contact of the device with the body. The terminal portions 12 of the backing plate will preferably contact the body in laterally spaced relation to the central portion 10 thereof. As mentioned previously, the aperture 50 will be located in registering or centering relation to the colostomy tube in the body. The member 32 is suspended freely from the front face of the backing plate and extends below the colostomy tube. When the belt is passed around the body and the device is connected with the body, the user may freely assume a seated position with the member 22 suspended between his legs.

In performing the colonic irrigation operation, the patient assumes a seated position, as upon a toilet seat, and grasps a catheter, shown fragmentarily at 70, which is connected at the end of a flexible tube 72 in turn connected to a source of liquid under pressure (not shown), such as an

elevated liquid container. The tube may have mounted slidably thereon a disk 74 formed of rubber or the like and provided with a small central opening having a snug fit upon the tube but accommodating sliding of the disk upon the tube. The plug 54 will have been removed from the opening 52 and will be freely suspended from the nipple by means of the cable or cord 64 which will preferably be of such length that the plug will be positioned adjacent to the opening 52 but may be swung laterally to a position clear of the opening 52. The catheter is then inserted through the openings 52 and 50 and into the colostomy tube in the manner well understood by physicians and colostomy patients, and the disk 74 is urged into flat face engagement with the front wall 36 of the member 32 to close and span the opening 52. The catheter 70 and tube 72 will each preferably be of a size substantially smaller than the size of the openings 50 and 52 to fit freely therein, as illustrated in Fig. 3, and the disk 74 will be of a size larger than the opening 52 so that it spans said opening and provides an effective seal therefor. When the parts are thus positioned, the supply of liquid through the tube and the catheter to perform the irrigation may commence.

After the required amount of liquid has passed through the tube and the catheter and into the colostomy tube in the body so as to complete the initial portion of the irrigation operation, the catheter 70 will be removed from the colostomy tube. The user can remove the tube with one hand and can grasp the plug 54 in the other hand, holding the plug 54 ready for insertion into the opening 52 as soon as the catheter has been removed. The insertion of the plug 54 closes the member 32 so that the material discharged is confined within the member 32 and permitted to pass therefrom only in a downward direction for discharge through the bottom opening 50 and the danger of splattering incident to the discharge pressure is completely overcome. It will also be apparent that, after the irrigation operation has been performed or while it is being performed and before the device is removed from the body, the tube 48 which has been connected with a faucet or other source of liquid, preferably separate from the source with which the tube 72 is connected, may have liquid discharged therethrough for the purpose of flushing the interior of the member 32. Such procedure is optional, however, and the flushing operation to clean the interior of the member 32 may be performed after the device has been removed. It will be observed in the latter connection that the device, by reason of its bottom or lower end opening 40 and, additionally, its registering openings 50 and 52, provides ready access to its interior for cleaning purposes.

It will be apparent from the above that all of the difficulties and inconveniences inherent in the performing of colonic irrigation by a colostomy patient are overcome. The patient is enabled to assume a comfortable and natural seated position and, except during the intake of the irrigation fluid when it is desirable to hold the catheter and its tube 72, the hands are completely free. There is no need to hold the container or other discharge barrier as has been necessary heretofore in performing an irrigation. Furthermore, it will be apparent that by the use of the backing plate and the positioning thereof flat against the body, the device will assume and maintain its proper position at all times and will

be held effectively against any tendency to tilt away from the body due to the suspended weight of the member 32. The member 32 in turn, even though formed of flexible or other material normally incapable of holding its shape, is extended at all times by the support 42 thereof so that the free discharge of irrigation through the member 32 will not be restricted.

While the construction and embodiment of the invention herein illustrated is preferred, it will be apparent that the construction of the device may be changed within the scope of the appended claims without departing from the spirit of the invention.

I claim:

1. A colostomy device comprising a backing member, a pad secured to said member at one face thereof, an elongated vertical hollow member secured to the opposite face of said member at the upper end of one wall portion of the hollow member, said hollow member having a discharge opening at its bottom and inner and outer access openings arranged in substantial alignment at its upper end portion, said backing member and pad each having an opening therethrough aligned and communicating with said inner access opening, a releasable closure for said outer opening, portions of said backing member projecting laterally relative to said hollow member and attachment means connected to the projecting portions of said backing member.

2. A colostomy device comprising a backing member, a pad secured to said backing at one face thereof, an elongated vertical hollow member secured to the opposite face of said backing member at the upper end of one wall portion of the hollow member, said hollow member having a discharge opening at its bottom and inner and outer access openings arranged in substantial alignment at its upper end portion, said backing member and pad each having an opening therethrough aligned and communicating with said inner access opening, said hollow member being formed of flexible material, and a reinforcing member carried by the upper end of said hollow member adjacent to said access openings said reinforcing member stiffening and shaping the upper part of the hollow member.

3. A colostomy device comprising a backing member, a pad secured to said backing at one face thereof, an elongated vertical hollow member secured to the opposite face of said backing member at the upper end of one wall portion of the hollow member, said hollow member having a discharge opening at its bottom and inner and outer access openings arranged in substantial alignment at its upper end portion, said backing member and pad each having an opening therethrough aligned and communicating with said inner access opening, said hollow member being collapsible, and a rigid reinforcing member carried by and fitting within the upper end of said hollow member to shape said hollow member and to space the portions thereof in which said access openings are formed.

4. A colostomy device comprising an apertured backing member, attachment means carried by said backing member, a flexible hollow member secured at its upper portion to said backing member and depending therefrom, said hollow member being vertically elongated and having an aperture communicating with said backing aperture, an access aperture spaced from and aligned with said first aperture and a drain opening at its lower end, and a reinforcing member

carried by and stiffening said hollow member adjacent said apertures, said reinforcing member being positioned at the level of said apertures and having at least one aperture therein communicating with an aperture of said hollow member.

5. A colostomy device comprising an apertured backing member, attachment means carried by said backing member at the front face thereof, a flexible hollow member secured at its upper portion to said backing member at the front face thereof between said attachment means and depending from said backing member, said hollow member being vertically elongated and having an aperture communicating with said plate aperture, an access aperture spaced from and aligned with said first aperture and a drain opening at its lower end, and a reinforcing member carried by and stiffening said hollow member adjacent said apertures, said hollow member having a top wall, and a tubular fitting carried by said top wall and communicating with the interior of said member.

6. A colostomy device comprising an apertured backing member, attachment means carried by 25 said backing member, a flexible hollow member

secured at its upper portion to said backing member and depending therefrom, said hollow member being vertically elongated and having an aperture communicating with said backing aperture, an access aperture spaced from and aligned with said first aperture and a drain opening at its lower end, a reinforcing member carried by and stiffening said hollow member adjacent said apertures, said hollow member having a top wall, a tubular fitting carried by said top wall and communicating with the interior of said member, a releasable closure for said access opening, and a flexible member connecting said fitting and closure.
